CEMENTING MACHINE

Clifford Roberts, Winchester, Mass., assignor to
 United Shoe Machinery Corporation, Paterson,
 N. J., a corporation of New Jersey

Application July 27, 1936, Serial No. 92,791

5 Claims. (Cl. 91—25)

This invention relates to cement-applying machines and is herein illustrated as embodied in a machine for applying cement to the margins of shoe soles.

5 In that type of shoe in which the sole is attached to the upper chiefly or wholly by means of an adhesive, hereinafter referred to as cement, it is the usual practice to apply a marginal band of cement to the shoe sole and another band of cement to the overlasted upper along the margin of the bottom of the shoe. When cements of the pyroxylin type are employed, it is customary to allow these coatings to dry and then to activate them by the application of a solvent. After this, the shoe and the sole are brought together and sole-attaching pressure is applied. With other types of cement in which rubber or a rubber substitute is a constituent, the use of an activator is not 10 usual as the sole and the shoe are brought together after a drying period and while the coatings are still adhesive.

In connection with some cements which are of the self-vulcanizing type, an accelerator is incorporated and is mixed with the cement prior to its application to the work to cause the vulcanization to take place at room temperature. With a cement of this type, it is not possible to mix quantities larger than those which are 15 to be employed in a few hours because of the danger that the vulcanization process will advance too far before the coating material is applied.

An object of this invention is to provide an 20 improved machine facilitating the mixture of component parts of a compound coating material directly in the machine by means of which the compound is to be applied to the work.

In the illustrated machine, in accordance with 25 features of the invention, separate reservoirs are provided, one for the cement and the other for the accelerator, with valves to control the delivery from said reservoirs directly into a mixing chamber provided with an agitator so that the components may be thoroughly intermingled prior to their application to the work. In view of the fact that only small quantities of the accelerator are needed for mixture with comparatively large quantities of the cement, the 30 reservoirs may conveniently be provided with measuring devices, such as graduated sight glasses, to enable the operator to let out the desired amounts from each reservoir into the mixing chamber.

35 These and other features of the invention will

be better understood from consideration of the following description taken in connection with the accompanying drawing, in which

Fig. 1 is an elevation of the head of a cement-applying machine involving my invention, and 5

Fig. 2 is a detail view in elevation taken from the right side of Fig. 1.

Although my invention may be employed with various types of cement-applying machines, it has been herein illustrated as utilized in connection with a machine of the extrusion type having a cement-applying nozzle 10 to which the margin of a shoe sole may be presented by co-acting feed rolls 12 and 14, the sole being guided by a gaging device 16. The lower feed roll 14 10 is mounted on a pivoted arm 18 having an extension 20 through which passes a control rod 22 joined to a lever 24. The flow of cement through the nozzle is controlled by a valve 26 and the valve is connected by means of a rod 28 and a lever 30 to this same control rod 22. Thus, whenever the levers 24 and 30 are turned under the actuation of a treadle rod 32, cement will flow through the nozzle and the feed rolls will be turned to present successive portions of 15 the margin of the sole for the application of cement. Power is supplied to the machine through a pulley 34 mounted on a drive shaft 36 and when the treadle rod is depressed, a clutch 38 is closed and power is supplied not only to the feed rolls but also to a gear pump 40 directly connected to an outlet 42 in a sump 20 25 30 35 40 forming part of a mixing chamber 46. From this gear pump 40, the cement is delivered under pressure through a pipe 43 to the nozzle 10. 35

The coating material is supplied to this mixing chamber 46 from reservoirs 48 and 50 cast as integral parts of a cover 52 for the mixing chamber, this cover being held thereon by one or more clamp bolts, such as that which is 40 shown at 54. From these reservoirs, the material contained therein is allowed to flow through outlet openings 56 and 58 into the mixing chamber whenever the ball valves 60 associated with said outlets are opened. These valves 45 have upright operating rods 62 normally held down by springs 64 but capable of being lifted by hand levers 66 or 68 secured to cross rods 70 and 72 pivotally mounted in ears provided on a top 74 for said reservoirs. To permit the 50 reservoirs to be conveniently filled, a hinged cover 76 (Fig. 2) common to the two is provided. When this cover has been closed, it is held in closed position by a clamp bolt 78. It will be observed that the cross rods 70 and 72 55

are provided with toe pieces 80 which underlie collars 82 secured to the upper ends of the associated valve rods 62. If desired, these reservoirs may be provided with sight glasses 84 having graduated scales 86 so that when the operator lifts the desired valve 60, he may, by inspection of the level of the fluid with respect to a scale 86, determine just how large a quantity is being let into the mixing chamber 46. In view of the fact that only a very small quantity of the accelerator is required for treatment of a charge of cement, the separate reservoirs 48 and 50 may, if desired, have cross sections having a ratio similar to the ratio of the two quantities. If this is the case, it will only be necessary for the operator to allow the level of the accelerator to fall as many graduations on its scale as the level of the cement has fallen.

Uniformity of the action of the accelerator on the cement depends in a large degree on the thoroughness with which these two components are mixed. Accordingly, agitator blades 90 and 92 are provided in the sump 44 of the mixing chamber. These blades are conveniently mounted on an upright shaft 94 which is journaled in a bearing 96 formed on the top 74 of the reservoirs and provided with a pulley 98 driven by a belt 100 passing over idlers 102 and a pulley 104. This latter pulley is secured to the drive shaft 36.

30. In the use of the machine, supposing that the reservoirs 48 and 50 have been supplied with the component materials, the operator will press first one and then another of the valve levers 66 and 68 and allow the desired quantities of the component materials to flow through the outlets of the reservoirs into the mixing chamber 46. Power having been supplied to the driving pulley 34, this material will be thoroughly mixed by the agitator blades 90 and 92 and be ready to be withdrawn through the outlet 42 by the pump 40 and delivered to the nozzle 10 whenever the operator depresses the treadle rod 32. This same action of depressing the treadle rod is also effective to raise the lower feed roll 14 thereby to grip the sole and cause successive portions of its margin to be presented to the nozzle 10 and coated with the compound coating material.

Having described my invention, what I claim as new and desire to secure by Letters Patent of the United States is:

50. 1. In a machine for coating the margin of a shoe part, a unitary structure comprising a frame supporting a cement-applying device as well as means for feeding the shoe part past the applying device to present successive portions of the margin thereto, and means also supported on the

frame for supplying cement to said applying device, said cement-supplying means comprising a plurality of storage reservoirs, a mixing chamber into which the storage reservoirs deliver, an agitator, in the chamber, valves for controlling the flow between the storage reservoirs and the mixing chamber and means for delivering mixed cement from the mixing chamber to the applying device.

2. In a machine for applying a band of cement to the margin of a shoe sole, a frame an extruding nozzle thereon, means supported on the frame adjacent to the nozzle for feeding the sole past the nozzle to present successive portions of the margin thereto, a mixing chamber on the frame, reservoirs for components of the cement, said reservoirs being carried by said mixing chamber and communicating with said reservoirs, means facilitating the withdrawal of measured portions of components from the reservoirs to the mixing chamber, an agitator in said mixing chamber, and means interposed between the mixing chamber and the nozzle for supplying cement under pressure to the nozzle.

3. In a machine for coating a shoe part, an applying device, a mixing chamber connected to said applying device to supply coating material thereto, a removable cover for said mixing chamber supporting supply reservoirs formed integrally with said cover, a cover for said reservoirs, and an agitator for said mixing chamber having a shaft journaled in the covers of said mixing chamber and reservoirs respectively.

4. In a machine for coating shoe parts, an applying device, a chamber connected to said applying device to supply coating material thereto, reservoirs adapted to contain components of said coating material, said reservoirs being provided with outlet openings leading to said chamber, valves controlling said openings, the cover for said reservoirs comprising a fixed covering portion and a movable covering portion, and actuating devices for said valves mounted on the fixed portion of said cover.

5. In a machine for coating shoe parts, an applying device, a mixing chamber connected to said applying device to supply coating material thereto, an agitator in said mixing chamber, means outside the chamber for driving the agitator, supply reservoirs mounted on the machine and arranged to deliver into said mixing chamber, covers for said reservoirs, and means on said covers and extending through the reservoirs, for controlling the flow between the reservoirs and the mixing chamber.

CLIFFORD ROBERTS.
